UNITED STATES PATENT OFFICE.

GEORGE CROMPTON, OF WORCESTER, MASSAC^USETTS.

IMPROVEMENT IN LET-OFFS FOR LOOMS.

Specification forming part of Letters Patent No. 42,461, dated April 26, 1864.

To all whom it may concern:

Be it known that I, GEORGE CROMPTON, of the city and county of Worcester, in the State of Massachusetts, have invented a new and useful Improvement in Let-Off Motions for Looms, of which the following is a full and exact description, reference being had to the accompanying drawings, making part of this specification, in which—

Figure 1 is a side elevation of a loom with said improvement applied thereto. Fig. 2 is a plan of the same.

The same letters indicate like parts in both figures.

My invention relates to that part of the loom known as the "let-off motion" for controlling the delivery of the warp from the warp-beam in a uniform manner, and is of that class of let-offs known as "tension let-offs," and which I will now proceed to describe.

Fig. 1 is a side elevation representing the ordinary frame of a loom. A is the warp-beam, which, with its gudgeons, rests on bearings L L. M M is the warp, passing from the beam over the roller E and under the roller F, and thence upward over the whip-bar or roller K to the harness. Friction-straps C C, fastened to the frame at N N, are carried over each beam-head, which have a groove cut into their peripheries B B, to receive the cords or straps, and are then continued and secured to the lever-frame D D. The rollers E and F are supported in suitable bearings, as seen in Fig. 2, at each end in their respective frames D D and G G, and are parallel to each other and the warp-beam. The frames D D and G G are respectively hung on pivots or studs at I I and H H, so they will hang freely, (bars may be used where rollers are shown, but I prefer the employment of rollers.) The frames containing the rollers are fender-like in form for the purpose of strength, so that when one end of the roller moves the opposite end will move with it. To the tension-roller frame is suspended a weight, J, of sufficient gravity to produce the requisite tension upon the warp.

The warp M M, passing from the warp-beam over what may be termed the friction-roller E in the frame D D, and then under the roller F in the upper frame, G G, and the tension-weight being attached thereto, bears upon the frame D D. The friction-straps, being attached thereto, produce friction and hold the warp-beam

firmly. As the weaving progresses, the weight J is gradually drawn up to such a point as to relieve the pressure on the friction-roller and frame, thereby slackening the friction-straps and allowing the gravity of the weight to draw off a portion of warp and lowering the weighted frame until its pressure is sufficient to tighten the friction-straps and hold the beam firmly until the tension-weight is again drawn up by the progress of weaving, when the friction is again relieved, and still more warp is yielded as before, and so on. The tension being the indicating-power, it liberates the friction upon the warp-beam whenever needing more warp for the weight to gravitate upon and produce tension, which is always uniform whatever may be the diameter of the beam.

In Fig. 2 it will be seen the rollers in the roller-frames D D and G G extend the entire width of the warp-beam and the warp is taken from it in perfect order, the frame-rollers being parallel therewith, and also with the whip roll or bar K. No slack selvages can be made. Each thread of warp is of an equal tautness, thus producing an equal strain on each thread of warp in weaving and more perfect selvages on the cloth when woven.

Other inventions have embraced the combination of tension with friction on the beam—as, for instance, using one weight for the tension of the yarn, and an independent weight for the friction on the warp-beam. The tension-weight in such case being so connected that when the tension-weight had reached its highest point, it would, when liberating the friction on the yarn-beam, have to raise the friction-weight, thereby creating an undue tension upon the warp while so engaged; or if using one weight for both tension of warp and friction to hold the beam, the friction was applied to the periphery of the yarn on the beam; or using one weight for tension attached to a roll, (but not in a framed lever or lever of any kind,) which, as it ascended by the progress of weaving and reached a certain point, elevated a friction-lever, (to which was attached the friction-strap to the beam,) allowing the tension-weight to draw off more warp from the beam, but this plan, like those previously alluded to, increases the tension of the warp-yarn while engaged in liberating the friction on the beam. Therefore these I do not claim, the points of my invention being so

constructing a let-off motion that the tension-roller and friction roller shall be sustained in rigid framed levers the width of the warp-beam, that in their operation they may be parallel with each other and the warp-beam, so as to prevent one side of the warp being more unduly strained than the other; and also so combining the tension and friction frames that as the former rises and diminishes its pressure upon the friction-frame it shall relieve the friction on the warp-beam for the purpose of letting off the warp, as described, and also combining the upper frame tension and weighted lever with the warp, and the warp beam, as herein described, for the purposes of tension on the warp and producing friction on the beam.

Having thus fully described my said invention, what I claim therein as new, and wish to secure by Letters Patent, is—

1. The combination of the tension and friction rollers or bars, and their respective frames,

the tension-weight, and warp-beam, with the warp as described.

2. The combination of the tension and friction framed levers and rollers or bars therein, and the tension-weight, with friction on the beam head or heads, as described.

3. The combination of the weighted tension framed-lever and roller or bar therein with the warp-beam, as described, for the purpose of producing tension on the warp and friction on the beam.

4. Diminishing or increasing the pressure of the tension frame roller or bar through the warp upon the friction-frame roller or bar by the tension-weight, for the purpose of relieving or holding the friction on the warp-beam.

In witness whereof I have hereunto subscribed my name the 22d day of January, 1864.

GEO. CROMPTON.

In presence of—

W. Y. McCAFFERTY,
GEORGE E. DUNLAP.
